P.C.(57) **CLAIM**

The ornamental design for a rapid diagnostic test reader, as shown and described.

DESCRIPTION

FIG. 1 is a top-front perspective view of a rapid diagnostic test reader;

FIG. 2 is a bottom-rear perspective view of the rapid diagnostic test reader of FIG. 1;

FIG. 3 is a front view of the rapid diagnostic test reader of FIG. 1;

FIG. 4 is a rear view of the rapid diagnostic test reader of FIG. 1;

FIG. 5 is a left side view of the rapid diagnostic test reader of FIG. 1;

FIG. 6 is a right side view of the rapid diagnostic test reader of FIG. 1;

FIG. 7 is a top view of the rapid diagnostic test reader of FIG. 1; and,

FIG. 8 is a bottom view of the rapid diagnostic test reader of FIG. 1.

The broken lines depict portions of the rapid diagnostic test reader that form no part of the claimed design.
